CLAIM

The ornamental design for a gas burner block for a molten steel vessel cover, as shown and described.

DESCRIPTION

FIG. 1 is a perspective view of the front of the gas burner block for a molten steel vessel cover of the present invention;

FIG. 2 is a front elevational view of the gas burner block for a molten steel vessel cover of FIG. 1;

FIG. 3 is a real elevational view of a gas burner block for a molten steel vessel cover of FIGS. 1 and 2;

FIG. 4 is a side elevational view of the gas burner block for a molten steel vessel cover of FIGS. 1-3 with all remaining sides being identical;

FIG. 5 is a perspective view of the rear of the gas burner block for a molten steel vessel cover of FIGS. 1-4.

The apparatus of the present invention is used for ladles and like containers that carry molten steel and like metals. The block apparatus of this invention receives a gas burner at its front which projects flaming gases through the circular opening shown in FIGS. 1 through 3. This opening extends through the apparatus from its front to its back.
